UNITED STATES PATENT OFFICE

WILLIAM J. ARCHER, OF WASHINGTONVILLE, OHIO, ASSIGNOR OF ONE-THIRD TO F. F. DE BOLT, OF EAST LIVERPOOL, OHIO.

GAME-BOARD.

1,025,940.

Specification of Letters Patent.

Patented May 7, 1912.

Application filed March 13, 1911. Serial No. 614,045.

To all whom it may concern:

Be it known that I, WILLIAM J. ARCHER, a citizen of the United States, residing at Washingtonville, in the county of Columbiana and State of Ohio, have invented certain new and useful Improvements in Game-Boards, of which the following is a specification, reference being had to the accompanying drawings.

10 My invention relates to new and useful improvements in games and more particularly to the class of games comprising a checkered board and a plurality of playing pieces therefor and my object is to provide 15 a game of this character which will require considerable thought and skill in the playing thereof and at the same time be extremely interesting both to young and old.

20 A further object is to provide a playing board, one face of which is provided with a central square surrounded by a plurality of smaller squares, said smaller and said central square being divided into smaller triangles.

25 A further object is to provide a plurality of playing pieces, one of which has a different identity from the others.

With these and other objects in view, my invention consists in the novel features of 30 construction, combination and arrangement of parts as will be hereinafter referred to and more particularly pointed out in the specification and claims.

35 In the accompanying drawings forming a part of this application, Figure 1 is a top plan view of the playing board. Fig. 2 is a top plan view of one of the playing pieces used, and, Fig. 3 is a similar view of another of the playing pieces used.

40 In carrying out my invention, I shall refer to the drawings in which similar reference characters designate corresponding parts throughout the several views and in which 1 indicates a board of any preferred size, but preferably octagonal in shape, as shown in the drawing, adapted to be placed on a table or the like, whereby a game may be played thereon. Said board 1 has one face thereof wholly divided into numerous 45 triangles 2 by the provision of a plurality of intersecting horizontal, vertical and diagonal lines drawn thereon and an outline encircling eight of the central triangles on said board, forms a central square 3 which

is designated from the other triangles by 55 being of a different color.

A plurality of the triangles surrounding the square 3 are outlined by means of the line 3^a and colored differently from the triangles surrounding the same, so that when 60 properly colored, there will be three sets of colored triangles, colored preferably as follows: The central square white, the collection of triangles surrounding the same, red, and the triangles surrounding said latter 65 collection, colored in blue, but I do not wish to limit myself to these colors and, of course, may use any colors desired so long as the three sets are colored differently. The outline of the outer collection of triangles is 70 provided with sixteen circles or dots and the outline of the middle collection of triangles is provided with twelve circles or dots, said 75 circles or dots being placed at the points of intersection of the lines forming the sides and bases of said triangles and the central square 3 is further provided with a central circle or dot at the points of intersection of the lines forming the triangles within said 80 central square, the purpose of which circles will be hereinafter and more particularly 85 described.

In order to play the game, twenty-eight 90 playing pieces 4 of the same identity and an additional playing piece 5 of a different identity than the other pieces are provided, said twenty-eight pieces being placed upon the twenty-eight circles on the outlines of the two collections of triangles and the additional playing piece being placed on the 95 central circle within the central square 3. As stated, this additional playing piece 5 is of a different identity than the playing pieces 4, and to this extent, any preferred forms of designs may be placed thereon which are appropriate to the name given the game.

This game is played as follows: The twenty-eight pieces 4 of the same identity are placed upon the twenty-eight circles or dots, above described, and the single piece 100 5 is placed in the central circle of the central square, it being understood that this game is to be played by two persons, one of whom is to care for the central figure, while the other takes charge of the twenty-eight surrounding men. For the sake of convenience, I shall refer to the central playing piece and the twenty-eight sur-

rounding pieces as the "outlaw" and the "detectives", respectively, and in moving the men, it must be understood that the same are to be moved on the lines forming the triangles, to the points of intersection thereof. The "outlaw" makes the first move and the "detectives" follow, each side moving alternately, and it will be here understood that the men forming the "detectives", may only move forwardly toward the center or on lines retaining them the same distance from said center, and said men may not "jump" the central figure when in position to do so, while said central figure or "outlaw" may move in any direction whatsoever at any time and may "jump" any of the "detectives" when unprotected, that is, when not followed immediately by an additional man. The central figure or "outlaw" may move around in any direction, as stated, as far as the outline ^{3a} and the "detectives" may move up to and on the line forming the square ³, and by allowing the "outlaw" to "jump" the various other men when unprotected, a method of elimination is provided.

The idea of the game is to have the "detectives" charge upon the "outlaw" in such forces as to prevent said "outlaw" from "jumping" said "detectives", thereby forcing him to move back into the central square ³. When the "outlaw" or central figure has been cornered in the central square so that he cannot move in any direction, the game has been won and it will be understood that it is possible for the central figure to be cornered beyond the central square, if the player be not so skilled as to prevent the same.

In playing the game, it will be appreciated that a great number of "detectives" will be "jumped" by the central figure, thereby eliminating them from the game, and by allowing the central figure to move in any direction, while the surrounding men may only move in restricted directions, considerable thought will be required to capture the central figure. If the central figure "jumps" such a great number of men as to prevent it being cornered, the game is, of course, won by the player having charge of said central figure.

It will be appreciated when this game is played properly, that a great amount of thought and skill is required so that the same will be doubtless interesting to both old and young. As the game also requires considerable forethought in the moving of the various men, it will be seen that the same is a wonderful training for the mind.

It may appear at first that this game with twenty-eight "men" on one side and one on the other is uneven or one-sided, but when considering the limitations of the twenty-eight "men", it will be appreciated that the ⁶⁵ chances are equal, possibly favoring the one "man".

What I claim is:—

1. A game of the class described, comprising a board having an octagonal outline thereon, the space inclosed by said outline being divided into a plurality of triangles, said triangles being arranged in sets and said sets distinguished from one another, one of said sets being outlined to ⁷⁰ form a substantial square, a plurality of playing pieces of the same identity, and an additional playing piece of a different identity.

2. A game of the class described, comprising a board having an octagonal outline thereon, the space inclosed by said outline being divided into a plurality of triangles arranged in sets, said sets being distinguished from one another and the apices ⁷⁵ of one of said sets being provided with certain indications, a plurality of playing pieces of the same identity adapted to be initially positioned on the aforesaid indications, and an additional playing piece of ⁸⁰ a different identity adapted to be initially positioned in a predetermined place on said board, the first mentioned playing pieces being limited in their movements on the board.

3. A game of the class described, comprising a board having an octagonal outline thereon, the space inclosed by said outline being divided into a plurality of triangles arranged in sets, each of said sets being distinguished from the other in color ⁹⁵ and the apices of the triangles in one of said sets being provided with certain indications, the triangles of one of said sets being outlined to form a substantial central square, a plurality of playing pieces of the same ¹⁰⁰ identity adapted to be initially positioned on the indications at the apices of the triangles in one set, and an additional playing piece of a different identity adapted to be initially positioned in the aforesaid central ¹⁰⁵ square, the first mentioned playing pieces being restricted in their movements on said board.

In testimony whereof I hereunto affix my signature in the presence of two witnesses. ¹¹⁵

WILLIAM J. ARCHER.
